THERMAL PIN FOR MEAT ROASTS

William Perez, Mineola, N. Y.

Application March 30, 1954, Serial No. 29,776

Term of patent 14 years

(Cl. D81—10)

Fig. 1 is a front view of a thermal pin for meat roasts showing my new design;

Fig. 2 is a bottom view thereof showing my new design; and

Fig. 3 is a top view thereof showing my design.

The dominant features of the design reside in the portions shown in full lines.

I claim:

The ornamental design for a thermal pin for meat roasts, as shown and described.
